UNITED STATES PATENT OFFICE.

HYMAN MUSKIN, OF BALTIMORE, MARYLAND.

SHOE MACHINE.

Application filed December 3, 1920. Serial No. 427,959.

To all whom it may concern:

Be it known that HYMAN MUSKIN, a citizen of the United States of America, residing at Baltimore, State of Maryland, has 5 invented new and useful Improvements in Shoe Machines, of which the following is a specification.

The object of the invention is to provide means in connection with shoe sewing or 10 stitching machines whereby the stitches may be formed perpendicular or substantially perpendicular to the plane of the shoe sole and extended through the sole to the under or outer or wearing surface thereof under 15 such conditions as to provide for the embedding and protection of the stitches or stitch elements at the outer or wearing surface against the effect of wear incident to the use of the shoe, and involving in that connection the formation in the outer or wearing surface of the shoe sole of a groove in which the stitches may be laid and protectively embedded; and in this connection to provide means whereby the preparation of 25 the outer sole member for the reception of the stitching, and consisting for example in the surface grooving thereof, may be effected progressively as the sole is stitched in the formation of the shoe.

Moreover it is the object to provide a grooving means for operation upon the exterior or wearing surface of the outer shoe sole member, in the preparation thereof for the embedding reception of the stitch members at the outer or wearing surface of the sole, which will act to temporarily displace a sufficient portion of the material of the face of the shoe sole to allow for the reception and embedding of the stitches, and to 30 hold the displaced portions thereof in a distended relation during the laying of the stitches, to permit of the subsequent resumption by such portions of their former or original positions to constitute a covering and 35 protection for the stitches and prevent the wear incident to the use of the shoe from being applied to the stitches.

With these and related objects in view as 40 will appear in the course of the following description, the invention consists in a construction, combination and relation of parts of which a preferred embodiment is disclosed in the accompanying drawing, it be-

ing understood that changes in form, proportion and details may be resorted to within 55 the scope of the appended claims without departing from the principles involved.

In the drawing:

Figure 1 is a plan view partly broken away of a shoe sewing machine, throat plate 60 and feeder with which is associated a grooving means constructed in accordance with the invention.

Figure 2 is a longitudinal sectional view of the same on the plane indicated by the 65 line 2-2 of Figure 1.

Figure 3 is an inverted plan view of the throat plate.

Figure 4 is a perspective view of the same.

Figures 5 and 6 are detail views respectively of the grooving carrier and bit, detached. 70

The device embodying the invention is illustrated in connection with the feeder mechanism of a machine of that type wherein in the needle hole, indicated at 10, is formed in one of the elements of the feeder of which the jaws 11 and 12, serrated as in the ordinary practice operate in slots 13 in the throat plate 14, and wherein the advance or work 75 feeding movement of the feeder, in the direction shown by the arrow in Figure 1 occurs while the stitching needle is in its depressed position and is in engagement with the work.

In cooperative relation with the feeder 80 and in the illustrated embodiment of the invention actuated by the feeder is a shoe sole grooving means consisting essentially of a carrier 15 mounted for reciprocatory movement in timed relation with the feeder, and 85 a bit 16 supported by the carrier and preferably formed as an independent element attachable thereto by means of a base plate 17 or the equivalent thereof held in place by retaining screws 18 or the equivalent 90 thereof, to the end that the bit may be replaced or interchanged with others of graduated sizes, may be suitably tempered, and may be detached for the purpose of sharpening the same and the like, said carrier being disposed in the path of the return movement of the feeder for repositioning thereby during its return stroke, after having advanced the work for the reception of the succeeding stitch, an actuating spring 19 95 serving to maintain the indicated relation 100

between the carrier and the feeder and hence acting to advance the carrier during the forward movement of the feeder.

The bit which is constructed to operate in a path parallel with the surface of the throat plate and projects above the plane thereof a distance corresponding with the depth of the proposed groove to be formed in the under surface of the shoe sole, is disposed for cutting action during the return movement of the feeder, and hence in such relation to the other parts of the mechanism as to form the groove in the shoe sole in advance of the formation of the stitches, but at such a short distance in advance of the intersecting path of movement of the needle as to serve as a means of holding the side walls of the groove formed by the bit in a laterally displaced or distended relation during the stitch forming operation of the needle, to insure the laying of the stitches in the groove, so that as the work further proceeds, and the side walls or displaced portions of the shoe sole are relieved of the distending action of the bit, said displaced walls in returning to their normal positions cover and conceal the stitches laid in the outer surface of the sole and interpose an appreciable thickness of the shoe sole material between the stitches and the wearing surface to protect the stitches from wear.

The bit, it will be noted, is of cross sectionally triangular form, thus providing diverging sides terminating at the cutting edge, the line of divergence being in the direction of movement of the bit. Further, the upper end of the bit is beveled rearwardly to leave a sharp point making for the easy initial penetration of the bit into the goods at the beginning of the channeling operation, the diverging side walls of the bit maintaining the distention of the slot or groove at the time of the laying of the stitches.

In the construction illustrated the carrier is mounted in a suitable guide formed by a longitudinal channel 20 in the surface of the throat plate, spanned by a bridge piece 21, and a down turned ear 22 at the extremity of the carrier supports a stud 23 with which one end of the spring 19 is engaged. The other end of the spring is fitted in a socket 24 in which is disposed a tension adjusting screw 25 designed to vary the stress of the spring 19 to insure a proper relation between the bit and the feeder, and the bit is of horizontally or cross-sectionally wedge shape as shown, being tapered toward its cutting edge, to effectively perform a spreading or distending action upon the walls of the groove as the operation thereof proceeds in advance of the formation of the stitches. Also as a means of reinforcing the relation between the bit and the carrier the base plate 17 of the former is preferably provided at the extremity adjacent to

the bit with a depending ear 26 for engagement with a seat 27 in the adjacent end of the carrier.

The invention having been described, what is claimed as new and useful is:—

1. A shoe sole stitching mechanism having, in combination with the bed plate, throat plate and feeder, a work channeling means having a reciprocable bit carrier mounted for sliding movement in a path parallel with the bed plate for forward and rearward movement with the feeder, a bit arranged close to and in the longitudinal plane of the needle for cutting action during the return movement of the feeder, the bit having a shank bearing upon the upper surface of the carrier and provided with a bearing ear for engaging the front end thereof, and the carrier having a depending ear for pressure by a bit actuating spring. 85

2. A shoe sole stitching mechanism having in combination with the bed plate, throat plate and feeder, a work channeling means having a reciprocable bit carrier mounted for sliding movement in a path parallel with the bed plate for forward and rearward movement with the feeder, a bit arranged close to and in the longitudinal plane of the needle for cutting action during the return movement of the feeder, the carrier and bit plate having depending ears of which that on the bit plate bears against the end of the carrier, and a spring bearing upon the ear of the carrier for maintaining the carrier in following relation with the feeder, and means for adjusting the tension of the spring to compensate for the rapidity of movement of the feeder. 95

3. The combination with a bed plate, the throat plate and the feed dog of a sewing machine; of a work-channeling member comprising a supporting plate slidably mounted beneath the throat plate and having a top channel, and a shank secured in said channel and having an upstanding blade at its forward end, the throat plate having a bottom slot in which the supporting plate seats, a retaining plate for said supporting plate extending across the bottom thereof, the throat plate also having an opening through which the blade protrudes, and the forward end of the shank being behind the feed dog to abut thereagainst to obtain a working stroke on the return stroke of the feed dog, a spring bearing against the rear end of the aforesaid supporting member, a socket for the spring mounted on the bottom of the bed plate, from which socket one end of the spring projects to engage the supporting member, and an adjustable abutment in the socket engaging the other end of the spring. 110 120 125

In testimony whereof he affixes his signature.

HYMAN MUSKIN.
